UNITED STATES PATENT OFFICE.

WILLIAM W. FRESCHL, OF PELHAM, NEW YORK.

PACKAGE-SEAL.

1,187,896.

Specification of Letters Patent. Patented June 20, 1916.

Original application filed March 12, 1913, Serial No. 753,740. Divided and this application filed June 25, 1913. Serial No. 775,641.

To all whom it may concern:

Be it known that I, WILLIAM W. FRESCHL, a citizen of the United States, and a resident of Pelham, in the county of Westchester and State of New York, have invented new and useful Improvements in Package-Seals, of which the following is a specification, reference being had to the accompanying drawings, in which—

10 Figure 1 is a perspective view of a package wrapped and sealed with a device embodying my improvements; Fig. 2 is a vertical section through the seal; Fig. 3 is a plan view of the blank before it is folded into position for use, and Fig. 4 shows the seal in folded and clamped position.

My invention relates to devices for sealing packages, in which a cord, rope or wire is employed, and my improvements consist in 20 mechanism for protecting the knot in the cord, rope or wire, thereby preventing the package from being opened by untying the cord, rope or wire. To this end I provide a seal which will inclose the knot and which 25 may be used with cords, ropes or wires of varying characters.

My improved seal is of simple and cheap construction and provides a closure for containing the knot and also serves to indicate 30 whether or not the package or its contents have been tampered with.

The foregoing and other objects of my invention are hereinafter more specifically described and claimed.

35 Referring to the drawings, the seal A is preferably formed of a single piece of sheet metal, which may be of any suitable shape but which I prefer to be substantially of circular form when completed. The seal A is comprised of two sides 2, 2' having a connecting piece 3. The connecting piece 3 has suitable apertures 4 through which the ends of the cord may be inserted. Upon the edges or lips 5 of the side 2 are integral 40 projections or studs 6, and the lips 5' of the other side 2' have orifices 7 for the reception of the studs 6. The sides 2, 2' have outwardly bowed portions 8, 8' which, when riveted or secured together, form a chamber 9 for the reception of the knot 10 to be tied in the cord 11.

My device is applied as follows. The package is tied in the usual manner with a cord 11 and is knotted, preferably as indicated

at 12. The loose ends of the cord 11 may 55 then be passed through the apertures 4 and a hard knot 10 tied adjacent the inner face of the connecting piece 3, and the loose ends may then be trimmed off, if desired. The folding of the blank A over the knot 10 60 may then be completed, thus causing the studs 6 to pass through the orifices 7, and any suitable tool may be used to upset or clench the studs 6 upon the lips 5' of the sides 2', as is shown in Fig. 2. The knot 65 will then be inclosed in the chamber 9 and will be inaccessible, since the lips 5, 5' of the sides 2, 2' will be held in close and firm contact by means of the upset studs or rivets 6. Any tampering with the studs 6 after 70 they have been upset will be readily ascertained upon inspection, and will indicate whether or not anyone had tried to loosen the seal and thereby untie the knot.

The present application is a divisional of 75 my co-pending application Serial Number 753,740, filed March 12, 1913.

It is obvious that various modifications may be made in the form of seal which I have shown and described herein without departing from my invention, since 80

What I claim is:

1. In a package seal, a one piece metal sheet apertured for the ends of a cord, a dish-shaped chamber formed between the 85 folded sides of the metal sheet adapted to completely inclose and protect a knot in the ends of the cord and locking means for the chamber comprising a plurality of studs integrally formed upon a lip of one of the 90 folded sides of the metal sheet and adapted when the folded sides are brought into contact to pass through openings in the lip of the other side and to be upset and expanded.

2. A closure for packages consisting of a 95 string passed around the package and a bendable metal sheet having perforations near its center of symmetry, through which the ends of the string are passed and knotted, the said sheet being folded along 100 the line of the perforations thus inclosing the knot in a dish-shaped metal chamber, the edges of which are riveted together.

WM. W. FRESCHL.
